RAILWAY SWITCH CONTROLLING APPARATUS

Application filed October 24, 1929. Serial No. 401,999.

This invention relates to the control of railway switches. One of the objects of the invention is to provide an improved system of switch control which affords protection 5 against misoperation of the switch motor in the event of the occurrence in the control circuits of a cross tending to cause improper rotation of said motor. Another feature of the invention comprises provisions for preventing a change in the setting of the switch 10 when a train occupies the track section in which the switch is located or when a train is approaching in an adjacent section. In addition we provide improved means for controlling the operation of a switch repeating relay adapted to control indications of the position of the switch, said means insuring that the switch control apparatus is properly 15 conditioned before the switch repeating relay 20 can be energized. Other features of the invention will be hereinafter described and claimed.

In the accompanying drawings:

Fig. 1 is a diagrammatic view of a control 25 system illustrative of our invention, and

Fig. 2 is a diagrammatic view illustrating another form of control means.

Referring to Fig. 1, a section of a railway track is shown at 2, in which section there is positioned a switch 3. A track relay is indicated at 5; while at 6 there is shown a motor, comprising an armature 7 and a field 8, for operating the switch. PR designates a polarized relay which may be controlled 35 manually, as by a dispatcher's system, or by any suitable or convenient remote control means, as will be readily understood, to cause current to flow through either coil 9 or coil 10, and thereby to move the armature 11 into 40 engagement with contact 12 or contact 13, for causing operation of the motor 6 in the desired direction.

The relay PR controls a pair of repeating stick relays 14, 15, in the circuits for controlling the switch actuating motor. Thus, with the armature 11 in engagement with contact 12, as shown, current may flow from terminal B of a suitable source of energy not shown in the drawing, through wire 16 (by way of 50 the armature 28 and contact 29, armature 30

and contact 31, and armature 33 and contact 34), and then through armature 11, contact 12, wire 17, armature 18 and back contact 19 of relay 15, wire 20, relay 14, wire 21, and wire 22 to terminal C of the same source; while, if armature 11 engages contact 13, a circuit is established from wire 16, through wire 23, armature 24, and back contact 25 of relay 14 (which relay is now de-energized), wire 26, relay 15, wire 27, and wire 22 to terminal C. We further provide a control over the relays 14 and 15 by the presence of a train in the track section 2. Relays 14 and 15 are also controlled by locking relays which may be controlled in accordance with usual and well known railway signalling practice to provide approach locking, route locking, stick locking, or time locking. For example, we have shown connected in circuit with the wire 16 an armature 28 and front contact 29 of the track relay 5; armature 30 and front contact 31 of a relay 32 responsive to the approach of a train in the track section adjoining one end of the section 2; and armature 33 and front contact 34 of a relay 35 responsive to the approach of a train in the track section adjoining the other end of said section 2. Relays such as the relays 32 and 35 are well-known in the art and need not be here described, it being sufficient to note that relay 32 or 35 is de-energized whenever a train is approaching section 2 in the corresponding adjoining track section. The track relay 5, as is well understood, is de-energized whenever a train occupies the section 2. The relays 5, 32, and 35 are provided with back contacts 36, 37, and 38, respectively, which are connected to a wire 39. Upon deenergization of any of said relays 5, 32, and 35, the connection from terminal B to the armature 11 of the relay PR is broken, and the wire 39 is connected with terminal B. Assuming

relay 14 to be energized through relay PR and any of the relays 5, 32, 35 to be de-energized, it will be seen that current will flow from terminal B, through the armature and back contact of said de-energized relay, wire 39, wire 40, armature 41, and front contact 42 of relay 14, wire 20, relay 14, and wires 21 and 22 to terminal C. Said relay 14 is thus

maintained energized as long as any one of the relays 5, 32, and 35 is de-energized, regardless of the position of the armature 11 of relay PR. Similarly, should relay 15 be energized when any of relays 5, 32, and 35 is de-energized, current would flow through wire 39, armature 43, and front contact 44 of relay 15, wire 26, relay 15, and wires 27 and 22 to terminal C, so that said relay 15 would remain energized as long as any of the relays 5, 32, and 35 is de-energized, irrespective of the condition of relay PR. It will thus be seen that the de-energization of any of the relays 5, 32, 35 will cause the relay 14 or 15 which at that time was energized to remain energized until said relays 5, 32, and 35 are all again energized. Thus, relays 14 and 15 will not be controlled by relay PR when a train is approaching section 2 in an adjacent section, or when a train is occupying said section 2, and the switch setting determined by said relays at the time any of the relays 5, 32, 35 becomes de-energized remains unchanged until all said relays are again in energized condition.

The relays 14, 15 control the operation of the switch motor 6 through contactor relays N and R. The relay N may be designated the normal contactor relay and relay R the reverse contactor relay. When the relay 14 is energized its armature 47 is engaged with contact 48 thereby connecting wire 49 to terminal B. A circuit is thereby closed through wire 49, armature 50 and back contact 51 of relay R, wire 52, contact 53, contact 54 which is operated by the switch and which is engaged with contact 53 at all times except when the switch is in full normal position, wire 55, relay N, and armature 56 and contact 57 of thermo cut-out 58 to terminal C. Relay N is thereby energized and a circuit is completed for the operation of the switch motor to move the switch from reverse position to its normal position. This circuit is from terminal B through the heating element 59 of the thermo cut-out 58, front contact 60 and armature 61 of relay N, wire 62, armature 7 of the switch motor 6, wire 63, armature 64 and back contact 65 of relay R, wire 66, and the field 8 of the switch motor to terminal C. The switch motor 6 thereupon operates the switch from reverse to normal position, and when the switch arrives at its full normal position the contact 54 which, as before noted, is actuated by the switch, is disengaged from the contact 53 so that the circuit through the relay N is broken as is likewise the circuit through said motor.

To effect operation of the switch from normal to reverse position, the relay PR is operated to close contact 11-18, so that relay 14 is de-energized and relay 15 is energized. Armature 67 of relay 15 is thereupon engaged with contact 68, whereby current flows from terminal B, through wire 69 connected

to armature 67, thence through armature 70 and back contact 71 of relay N, contact 72, armature 73 which is operated by the switch, and which is in engagement with contact 72 at all times except when the switch occupies its full reverse position, wire 74, relay R, and armature 75 and contact 76 of thermo cut-out 77 to terminal C. Relay R is thereby energized and closes a circuit through the switch motor 6 for operating the latter to move the switch to reverse position. This motor circuit is from terminal B through the heating element 78 of thermo cut-out 77, front contact 79 and armature 64 of relay R, wire 63, motor armature 7, wire 62, armature 61 and back contact 80 of relay N, wire 66 and motor field 8 to terminal C. When the switch motor has moved the switch to full reverse position, the switch operated contact 73 is disengaged from contact 72 whereby relay R is de-energized and the switch motor circuit opened.

Assuming that a cross occurs on the control circuit for contactor relay R when the apparatus is in normal condition, as shown in Fig. 1, with the result that the relay R would be energized at an improper time the armature 50 would engage front contact 81 of said relay R so that a circuit would be completed through contactor relay N from terminal B through front contact 48 and armature 47 of relay 14, wire 49, contact 50, and front contact 81 of relay R, wire 82 to wire 55 and thence through relay N and armature 56 and contact 57 of thermo cut-out 58 to terminal C. It will thus be seen that said cross on the reverse control circuit would result in the energization of both contactor relays N and R with consequent engagement of armature 61 with front contact 60 of relay N and armature 64 with front contact 79 of relay R, thus causing the motor armature 7 to be shunted and the circuit through the motor field 8 to be opened, and thereby preventing operation of the switch by said motor. Conversely, if a cross should occur on the control circuit for contactor relay N, resulting in improper energization of said relay N when the relay 15 is energized and the switch is in the reverse position, the engagement of armature 70 of relay N with front contact 81 closes a circuit from terminal B through front contact 68 and armature 67 of relay 15, wire 69, armature 70 and front contact 70' of relay N, wire 74, relay R, and thence through armature 75 and contact 76 of thermo cut-out 77 to terminal C. Thus again both the contactor relays N and R are energized, the motor armature shunted, and the motor field circuit opened so that operation of the switch is prevented. It will thus be apparent that improper operation of the switch, as the result of the occurrence of a cross on the control circuit for either contactor relay N or R, is

prevented from causing operation of the switch. Assuming, however, that during the existence of a cross on the control circuit for contactor relay R the operator should cause the armature 11 of the polarized relay PR to shift from engagement with contact 12 into engagement with contact 13, relay 14 would be de-energized and the circuit through contactor relay N broken by the disengagement 5 of armature 47 from front contactor 48 of said relay 14. Armature 61 of relay N would thereupon drop into engagement with back contact 80. Inasmuch as contactor relay R is at this time energized, a circuit is established through the switch motor for moving the switch to reverse position. The occurrence of a cross on the control circuit for relay R at a time when relay 14 is energized, while causing energization of relay N and preventing 10 operation of the switch motor as long as said relay 14 is energized, does not prevent operation of the switch to reverse position in response to energization of relay 15, and the apparatus therefore permits movement of the switch to reverse position when the operator intends that such reversal should occur. Also, the existence of a cross on the control circuit for relay N, when the relay 15 is energized, while establishing a circuit through relay R, and thus preventing switch operation, 15 does not preclude actuation of the switch to normal position when contact 11—12 of relay PR is closed to energize relay 14, since at this time relay 15 is de-energized and the circuit 20 through contactor relay R is broken by the disengagement of armature 67 from front contact 68 of relay 15 with consequent engagement of armature 64 with back contact 65 of relay R, and the establishment of a circuit 25 through front contact 60 and armature 61 of relay N through the motor for operating the switch to normal position.

At 90 we have shown a switch repeating relay which is adapted to close circuits to effect various indications or controls in accordance with the position of the switch. Such relays are well-known and we have shown the relay 90 as controlling circuits through lights 91, 92, respectively, for indicating the position of the switch, though said relay may also enter into the control of signals or other devices in accordance with the switch position. Armature 93 of said relay is polarized, and is engaged with the contact associated with 91 or the contact associated with 92 depending upon the direction of the flow of current through said relay 90; so that upon a flow of current in one direction through said relay, light 91 will be illuminated, while light 92 will be illuminated upon flow of current through said relay in the other direction. When the relay 90 is de-energized the circuit to the armature 93 is broken by the dropping of armature 94 out 30 of engagement with contact 95, so that neither

light 91 nor light 92 is illuminated. The flow of current through relay 90 is controlled by contacts operated by the switch. When the latter is in normal position, contact member 96 is engaged with contact 97, thereby connecting wire 98 to terminal B. Assuming the contactor relays N and R to be de-energized, relay 14 to be energized and relay 15 de-energized, current can now flow from terminal B through wire 98, back contact 99 70 and armature 100 of relay N, wire 101, front contact 102 and armature 103 of relay 14, wire 104, relay 90, wire 105, armature 106 and back contact 107 of relay 15, wire 108, armature 109 and back contact 110 of relay N, wire 111, contact member 112, and contact 113 to terminal C. Light 91 is thereupon 75 illuminated to indicate that the switch is in normal position.

If, on the other hand, the switch is in reverse position, the contactor relays N and R de-energized, relay 14 de-energized, and relay 15 energized, current will flow from terminal B through wire 114, contact 115, switch operated contact 116 (which is engaged with contact 115 by movement of the switch to reverse position), wire 117, back contact 118 and armature 119 of relay R, wire 120, front contact 121 and armature 106 80 of relay 15, wire 105, relay 90, wire 104, armature 103 and back contact 122 of relay 14, wire 123, armature 124 and back contact 125 of relay R, wire 126, switch operated contact 127, and contact 128 to terminal C. Armature 93 of relay 90 is thereby swung to 85 engage a contact in circuit with light 92 and the latter is illuminated.

It will be seen that the circuits for the control of the switch repeating relay 90 include, in addition to contacts operated by the switch, contacts controlled by the contactor relays N and R, so that de-energization of said relays is required before a circuit can be closed through relay 90. Should either contactor relay be energized the circuit for relay 90 would be opened and said relay 90 shunted. The control circuits for relay 90 also include contacts controlled by the relays 14 and 15, as has been noted, so that said relays must be in condition corresponding to the setting of the switch before relay 90 can be energized.

Whenever the relay 90 is not energized, its non-polarized armature 94 is out of engagement with contact 95, so that neither of the lights 91 or 92 is illuminated. An indication is thereby afforded that the switch is not in the position corresponding to the setting of the switch control relays 14, 15, so that one or both relays N, R, may be in energized condition.

In Fig. 2 we have shown a modified form of switch control system, wherein a polarized relay 129 is substituted for the two relays 14, 15. In this modification, when arma-

ture 11 of relay PR engages contact 12, current flows through wire 16, armature 12, contact 11, and wire 17, as in Fig. 1, thence through wire 130, through one winding of relay 129, and wire 131 to terminal C. If armature 11 engages contact 13, current flows through wire 132, through another winding of relay 129, and thence through wire 131 to terminal C. Armatures 133-136, inc. of relay 129 are polarized, while armatures 137, 138, and 139 are not. It will be seen that wire 39 is connected to armature 133 whereby if a train is approaching or occupying the track section 2 current will be maintained through that winding of relay 129 which was energized at the time of such approach or occupancy. Thus, when current is flowing through wire 130 to relay 129, armature 133 engages contact 140, so that upon the throwing of wire 39 in circuit in place of wire 16, by the de-energization of any relay 36, 37, or 38, current will flow through wire 39, armature 133, contact 140, wire 141, wire 130 and wire 131 to common return, thus maintaining energized the winding of relay 129 which is energized when armature 11 of relay PR is engaged with contact 12. When armature 11 engages contact 13 and current thereby flows through wire 132 to relay 129, armature 133 of said relay engages contact 142, so that upon de-energization of any one of relays 36, 37, 38, current flows through wire 39, armature 133, contact 142, wire 143 to wire 132, thus maintaining energized that winding of relay 129 which is energized when armature 11 engages contact 13.

When current is flowing through relay 129 through wire 130, armatures 134, 135, and 136, engage respectively the contacts 144, 145, and 146. Wire 49 of Fig. 1 is connected to contact 144 so that when current flows through said relay 129 by way of wires 130 and 131, wire 49 is connected to battery through armatures 134 and 139 for controlling operation of the switch to normal position. Similarly, wire 69 is shown connected to contact 145 so that when current flows through relay 129 by way of wires 132, 131, wire 69 is connected to battery through armatures 134 and 139 for controlling operation of the switch to reverse position. Also, the wires 101, 108 of Fig. 1 are shown connected to contacts 146, 145, respectively, in Fig. 2, so that when armatures 135, 136 engage said contacts, said wires 101, 108 are connected to wires 104, 105, through armatures 137, 138 respectively, for passing current in one direction through the switch repeating relay 90. Also, wires 120, 123 of Fig. 1 are shown in Fig. 2 connected to contacts 147, 148 respectively, so that when armatures 135, 136 engage the last mentioned contacts in response to flow of current through the winding of relay 129 connected to wires 132, and 131, the wires 120, 123 are

connected through armatures 137, 138 to wires 105, 104, respectively, for passing current in the appropriate direction through relay 90. The energization of the latter is thus conditioned upon the proper setting of the switch control relay 129.

It may be further pointed out that the protection which we have provided against mis-operation of the switch upon the occurrence of a cross on the control circuit for either of the contact or relays N, R, is obtained regardless of whether the relays 14, 15 of Fig. 1, or the polarized relay 129 of Fig. 2 be employed. In fact, as will be apparent, other means such as a contact lever could be employed in place of relays 14, 15 or of relay 129, for controlling the contactor relays N, R, by connecting either wire 49 or wire 69 to battery, and the cross protection hereinbefore described in connection with the circuits through those wires would continue to be effective.

Also, it may be noted that if a break should occur in the control for either of the contactors N, R, a failure of operation would result, which would be indicated at the switch repeating relay 90.

The terms and expressions which I have employed are used as terms of description and not of limitation, and I have no intention, in the use of such terms and expressions, of excluding any mechanical equivalents of the features shown and described or portions thereof, but recognize that various structural modifications are possible within the scope of the invention claimed.

What we claim is:

1. In a switch control apparatus, a motor for operating the switch, a pair of relays for establishing circuits through said motor to cause the latter to move the switch to either normal or reverse position according as one relay or the other is energized and for preventing operation of said motor when said relays are concurrently energized, selective means and circuit connections controlled thereby for energizing either of said relays to effect the desired setting of the switch, contacts controlled by said switch for breaking the circuit through the selected relay upon the arrival of the switch at its desired setting, and means comprising a front contact of the non-selected relay for energizing the selected relay in response to energization of said non-selected relay when said selective means is in a condition for selecting the selected relay.

2. In a switch control apparatus, a motor for operating the switch, a pair of relays for establishing circuits through said motor to cause the latter to move the switch to either normal or reverse position according as one relay or the other is energized, and for preventing operation of said motor when said relays are concurrently energized, selective

means and connections for energizing either of said relays, the connections for energizing one of said relays including an armature and a back contact of the other, contacts controlled by said switch for breaking the circuit through the selected relay upon the arrival of the switch at its desired setting, and connections comprising said armature and a front contact of the non-selected relay for energizing the selected relay in response to energization of said non-selected relay when said selective means is in a condition for selecting the selected relay.

3. In a switch control apparatus, a motor for operating the switch, a normal switch relay and a reverse switch relay, a normal control relay and a reverse control relay, means for selectively energizing the normal or the reverse control relay; a circuit for said normal switch relay including a front contact of the normal control relay, a back contact of the reverse switch relay, and a contact which is operated by the switch and is closed in all positions of the switch except normal; a circuit for said reverse switch relay including a front contact of the reverse control relay, a back contact of the normal switch relay and a contact which is operated by the switch and is closed in all positions of the switch except reverse; an auxiliary circuit for said normal switch relay including a front contact of the normal control relay and a front contact of the reverse switch relay, an auxiliary circuit for said reverse switch relay including a front contact of the reverse control relay and a front contact of the normal switch relay, and means for operating said motor to move the switch to normal or reverse position according as the normal or the reverse switch relay is energized and for preventing operation of said motor if said two switch relays are concurrently energized.

4. In a switch control apparatus, a motor for operating the switch, a normal switch relay and a reverse switch relay, relay means for selectively energizing either of said switch relays, a circuit for said normal switch relay including a contact of said relay means, a back contact of the reverse switch relay and a contact which is operated by the switch and is closed in all positions of the switch except normal; a circuit for said reverse switch relay including another contact of said relay means, a back contact of the normal switch relay and a contact which is operated by the switch and is closed in all positions of the switch except reverse; an auxiliary circuit for said normal switch relay including a contact of said relay means and a front contact of the reverse switch relay, an auxiliary circuit for said reverse switch relay including a contact of the relay means and a front contact of the normal switch relay, and means for operating said motor to move the switch to normal or reverse position according as

the normal or reverse switch relay is energized and for preventing operation of said motor if said two switch relays are concurrently energized.

5. In a switch control apparatus, a motor for operating the switch, a normal switch relay and a reverse switch relay, a polarized relay for selectively energizing either of said switch relays, a circuit for said normal switch relay including a contact of said polarized relay, a back contact of the reverse switch relay and a contact which is operated by the switch and is closed in all positions of the switch except normal; a circuit for said reverse switch relay including another contact of said polarized relay, a back contact of the normal switch relay and a contact which is operated by the switch and is closed in all positions of the switch except reverse; an auxiliary circuit for said normal switch relay including a contact of said polarized relay and a front contact of the reverse switch relay, an auxiliary circuit for said reverse switch relay including a contact of the polarized relay and a front contact of the normal switch relay, and means for operating said motor to move the switch to normal or reverse position according as the normal or reverse switch relay is energized and for preventing operation of said motor if said two switch relays are concurrently energized.

In testimony whereof, we have signed our names to this specification this 22 day of October, 1929.
